TYPOGRAPHICAL MACHINE

Herman R. Freund, Brooklyn, and Arthur G. Sperry, Hollis, N. Y., assignors to Intertype Corporation, Brooklyn, N. Y., a corporation of New York

Application January 26, 1934, Serial No. 708,490

20 Claims. (Cl. 199—49)

The present invention relates to improvements in typographical or line composing machines and more especially to those of the general class disclosed in U. S. Letters Patent No. 436,532 granted September 16, 1890 wherein character bearing matrices stored in a magazine are delivered therefrom under control of a keyboard and composed or assembled into lines which are delivered to a line transporter or so-called first elevator, the latter operating to lower each line from the level at which it is delivered thereto to a position in front of a mold, the casting mechanism of the machine operating to inject metal into the mold to cast a type bar or slug against the character bearing face of the matrix line, and, in the normal cycle of operation of such machines, the line transporter or first elevator, after the cast has been made from the line, ascends to lift the matrix line from the casting position or level, past the line delivery level, to an upper transfer level where the line is removed from the line transporter and the matrices conveyed to distributing mechanism by which the matrices which composed the line are returned to the magazine from which they were drawn, after which the line transporter or first elevator returns to its normal line receiving level.

The usual typographical machine of this class consists of keyboard composing, casting and distributing units organized into a unitary machine for successive correlative functioning during each operating cycle in the production of a type bar or slug.

Broadly, these machines are designed primarily for text composition on a mass production basis, their capacity being enlarged to a limited degree to enable the production of type slugs with printing faces of somewhat larger size than used for text by arranging them to carry three or even four fonts of matrices, this being the practical limit. Their capacity, however, is restricted with respect to the number and sizes of type faces that can be produced economically by such factors as the operating range of the composing unit comprising essentially the keyboard and the magazines, certain parts of the distributing unit, and also the matrices themselves, which, for the large type faces, become too large and too heavy to be practical for automatic assembly and distribution.

A large number of odd lines in different styles and sizes of type faces are required in order to satisfy the varied range of printed matter to be produced from type slugs and while it is true that these machines can carry several fonts of

matrices at a time, this capacity falls far short of being practical because the large number of styles and sizes of type lines demanded during the course of a day would entail the constant exchanging of magazines merely to cast, in many cases, only one or two odd lines from a particular font.

In present practice the requirements are met either by hand composing the odd lines with auxiliary matrices, commonly called side sorts, inserting them into the assembling box of the machine and after casting a line therefrom, removing and distributing them by hand into the sorts box from which they were taken, or, instead of employing these automatic machines, the odd lines may be produced on special machines designed only for casting from hand set lines. The former method is too slow and inefficient with the machines as now constructed, while the latter method involves additional investment in equipment and higher operating costs.

The primary object of the present invention provides such improvements as will enable keyboard composing machines to be employed with efficiency and economy for casting odd lines in all sizes and styles of type faces, particularly in sizes now beyond the range of these machines, thus giving such machines greater flexibility and a wider range of usefulness and thus eliminating to a large extent the necessity of special casting machines.

According to the present invention, the increased flexibility is attained by providing for the selective use of the casting unit independently of the composing and distributing units and by providing convenient means whereby the operator can quickly insert, cast from and remove lines of matrices composed by hand. To this end the invention provides simple mechanism for modifying the operating cycle of the machine according to whether a cast is to be made from a hand set or a keyboard composed line, such mechanism being so correlated with the conventional machine as to avoid interference therewith and with the operation thereof in the usual manner for casting slugs from lines of matrices set from the keyboard. Thus the machine may be operated as a simple casting unit at any time and at the completion of each modified operating cycle, the parts involved in altering its operation are returned automatically to their normal or usual relationship ready for instant selective use either for keyboard composing, casting and distributing in the conventional manner, or for casting only, from hand set matrix lines.

To these and other ends, the invention consists in certain improvements and combinations and arrangements of parts all as will be hereinafter more fully described, the features of novelty being pointed out particularly in the claims at the end of this specification.

In the accompanying drawings:

Figure 1 is a side elevation of a portion of a typographical machine to which the preferred embodiment of the present invention is shown applied;

Figure 2 is a top plan view partly in section of a portion of the structure shown in Fig. 1;

Figure 3 is a detail perspective view of a portion of the structure shown in Fig. 2;

Figures 4 and 5 are side elevations of the first elevator controlling means, showing the same respectively in the positions they occupy at different parts of the cycle of operation;

Figure 6 is an elevation of the first elevator controlling means as viewed from the left in Fig. 1;

Figure 7 is a view similar to Fig. 1 but showing another embodiment of the invention;

Figure 8 is a front elevation of a portion of a typographical machine equipped with the embodiment of the invention shown in Figs. 1 to 3 inclusive; and

Figure 9 is a detail horizontal cross-section taken on the line 9-9 in Fig. 8.

Similar parts are designated by the same reference characters in the several figures.

The present invention is especially applicable to typographical machines of the class hereinbefore referred to, and it is shown so applied in the present instance. Since the construction and mode of operation of machines of this class are well known to those skilled in the art, it is deemed sufficient for the purposes of the present invention to show and describe herein the casting mechanism with which the keyboard controlled composing mechanism and the matrix distributing mechanism cooperate in the usual and well known way. The casting unit of the machine as shown comprises the usual main frame 1 in which the usual mold wheel 2 is mounted, the usual vise frame 3 for supporting the matrix lines in casting position in front of a mold on the mold wheel, as usual, and a metal pot 4 which is movable in the usual way against the rear face of the mold 50 and is operative to inject molten metal into the mold cavity to cast a type bar or slug therein. The machine also comprises a line transporter 5 which as shown corresponds with the usual so-called first elevator, this elevator having the usual jaws 6 adapted to receive a line of keyboard-set matrices and spacebands from a delivery channel A in the usual manner while in its normal position, the elevator being guided to slide vertically on the vise frame to lower the matrix line into casting position in front of the mold, and, after the cast, to lift the matrix line to an upper level at which the line is transferred from the first elevator through a transfer channel B, by the usual means, to a so-called second elevator 7, the second elevator then lifting the matrices up to the usual distributing mechanism of the machine which returns the matrices to the respective channels of the magazine from which they were drawn, as well understood by those familiar with machines of this class.

The first elevator herein shown may be of the usual construction with the exception however that the head 8 at the upper end thereof and which carries the line receiving jaws 6 is pivoted 75 to the lower or slidably guided portion thereof

by a horizontal pivot 9, whereby this portion of the elevator, while the latter occupies its normal level or line receiving position as shown in Figure 1, may be swung forwardly as indicated by the dotted lines in Figure 7 and thereby bring the jaws 6 into a position which enables a matrix line to be conveniently introduced into and removed from the elevator. A handle 10 is preferably provided on the head 8 to facilitate the swinging thereof into forward position for introduction or removal of a line and for return of the head 8 to its normal position as shown in Figure 1, it being understood that when the head 8 is in the latter position, the jaws 6 will be in position to lower a matrix line into casting position in front of the mold and to elevate the matrix line from such position. The first elevator has a lower body portion 105 the rear bearing surface of which slides vertically on a front bearing surface 106 on the vise frame 3, and said body portion of the elevator has bevelled side bearing surfaces which slide vertically in guides 107 fixed to the front of the vise frame, and in order to lock the pivoted head 8 on the upper end of the elevator from swinging out of its normal upright position while carrying a line to or from casting position in front of the mold, the head is provided with an extension 108 which is a continuation of the lower body portion of the elevator when said head occupies its upright position, this head (see Fig. 9) having a rear bearing surface 109 which is a continuation of that of the body portion of the elevator and having bevelled side bearing surfaces 110 which are continuations of those of the lower portion of the elevator, the bearing surfaces on the head thus being coextensive in cross section with those of the lower portion of the elevator and cooperating with the bearing surface 106 on the vise frame and the guides 107 thereon, when the elevator is lowered from its normal line receiving position, to lock the head against swinging out of its upright position, thus insuring the proper lowering of the lines into the usual vise, in casting position, and removal of the lines therefrom. The operation of the first elevator is controlled by a lever 11 which is operatively connected to the lower body portion 105 of the elevator by a link 12 and is fixed to a shaft 13, these parts being similar to the first elevator lever and link commonly used in machines of this class.

According to the present invention, means is provided for controlling the ascent and descent of the first elevator whereby it may be caused to descend from its normal line receiving position as shown by the full lines in Figures 1 and 7 to its lower or casting level as shown by the dotted lines in Figure 7 and thereby present a matrix line in front of the mold for the casting of a type bar or slug therefrom, and to then ascend to the upper level, as indicated by the dot and dash lines in Figure 7, for the transfer of the line therefrom to the second elevator which serves to convey the matrices to the distributor, and finally lower the elevator to its normal position as shown by the full lines in Figures 1 and 7, so that the machine may perform the cycle usual when the matrix lines are composed by manipulation of the usual keyboard in the machine, or the elevator may be caused to descend from its normal position as shown in Figure 1 or by the full lines in Figure 7, after receiving a matrix line, to the lower or casting level, as indicated by the dotted lines in Figure 7, to pre- 75

sent the matrix line in casting position in front of the mold, and after the cast has taken place, to return directly to its normal position as shown in Figure 1 or by the full lines in Figure 7, as when casts are to be made from hand set matrix lines.

The means shown in the present instance for accomplishing this result comprises a duplex cam 14, one portion of which embodies sections 15, 16 and 17 for positioning the first elevator at the normal, lower and upper levels respectively, the contour of this portion of the cam corresponding to that of the usual first elevator cam, and the other portion of the duplex cam embodying sections common to the sections 15 and 16, and a section 18 which is a concentric continuation of the cam section 15. This duplex cam is fixed on the usual main cam shaft 19 of the machine, this shaft being mounted rotatably in suitable bearings in the main frame and having driving means therefor which causes it to make one revolution during each cycle of operation of the machine. The shaft 13 has a lever 20 pinned or otherwise fixed thereto, this lever carrying a roller 21 which rides on the cam portion having the section 18 thereon, and a cam lever 22 is mounted loosely or rotatably on the shaft 13 and carries a roller 23 which rides on the portion of the duplex cam embodying the sections 15, 16 and 17. Means is provided for connecting and disconnecting the levers 20 and 22 so that they may be caused to operate either in unison or independently of one another, such means comprising in the present instance a latch 24 which is pivotally connected to the lever 22 at 25 and has a notch or recess 26 adapted to receive a stud 27 projecting from a side of the lever 22 when these levers are opposed to one another as shown for example in Figures 4 and 5, these levers being then connected for operation in unison, the travel of the roller 23 of the lever 22 on the sections 15, 16 and 17 of the cam causing the first elevator to operate according to the usual or conventional cycle, as when the lines are composed under the control of the keyboard and the matrices composing the line are returned to the magazine by the distributing mechanism in the machine, after the cast has been made, and when the latch 24 is lifted to disengage it from the stud 27, as shown in Figs. 1 and 7, the roller 23 of the cam lever 20 may ride upon the raised section 17 of the duplex cam while the roller 21 of the cam lever 20 rides on the section 18 of the cam, and since the lever 20 is fixed to the shaft 13 to which the first elevator lever 11 is fixed while the lever 22 is mounted loosely on said shaft, the first elevator will be returned directly from casting level to its normal level as shown in Figure 1 and by the full lines in Fig. 7, instead of being lifted to a higher level for transfer of the matrix line to the second elevator for distribution, this modified cycle of operation being particularly suitable for casting from hand set lines. The latch 24 may be moved into connecting and disconnecting relation with the lever 22 by suitable means, preferably a toggle 28, the ends of which are pivotally connected to the latch and to the lever 20, the toggle when flexed causing the latch to engage the stud 27 and thereby connect the levers 20 and 22 as shown in Figs. 4 and 5 and when straightened disengaging the latch from the stud 27 and thereby disconnecting the levers 20 and 22, as shown in Figs. 1 and 7. In order to prevent the roller 23 on the lever 22 from dropping away from the cam when the latch is in disconnecting position, a

tension spring 29 may be attached at its ends to the levers 20 and 22 as shown, this spring however permitting the roller 23 to ride on the raised section 17 of the cam while the roller 21 rests on the relatively lower section 18 of the cam, under the weight of the elevator.

The latch 24 constitutes means for selectively setting the cam control means for the first elevator whereby the latter may be caused to operate in accordance with the conventional cycle of the machine or to return directly to its normal position after presenting the matrix line to casting position, as when casting from hand set lines. In the embodiment of the invention shown in Figs. 1, 2 and 3, means is provided for automatically starting the machine into operation when the latch 24 is set in disconnecting relation with the lever 22 so that the elevator will descend from its normal position to present a matrix line in casting position and return directly to normal position. Such means, as shown in the present instance, comprises a rock shaft 30 mounted in suitable bearings in the machine, this shaft having a crank arm 31 fixed thereon and operatively connected by a link 32 to the middle pivot of the toggle 28, the shaft 30 also having a crank arm 33 fixed thereon and pivotally connected to a rod 34 which is mounted to reciprocate longitudinally in the machine and extends to the front thereof, an operating lever 35 being pivoted at 36 to the vise frame 3 and extending up into proximity to the movable head 8 of the elevator, and having its lower end arranged to bear against the forward end of the rod 34. By this arrangement, when the upper end of the lever 35 is pulled forwardly or toward the right in Fig. 1, its lower end will push the rod 34 and thereby rock the shaft 30 to swing the crank arm 31 thereon in a direction to straighten or spread the toggle 28, the toggle then acting to lift the latch 24 out of engagement with the stud 27 on the lever 22, the latter lever being thereby disconnected from the first elevator lever 11 so that the operation of the latter will be under control of the lever 20. In order to automatically return the latch 24 to engaged relation with the lever 22 prior to the commencement of the next operating cycle of the machine, the rod 34 is extended rearwardly and arranged to abut against a lug 37 provided on the usual ejector lever 38 of the machine which is actuated by a cam 39 carried by the usual driving gear 40 fixed to the cam shaft 19, so that as the ejector advances to remove from the mold the type bar or slug cast therein, the rod 34 will be pushed forwardly, thereby rocking the shaft 30 in a direction to flex the toggle 28 and thereby allow the latch 24 to become reengaged with the stud 27 on the lever 22 when the latter returns to a position directly opposite to the lever 20, as shown in Figs. 4 and 5. The lower portion of the lever 35 is arranged to bear against a lug 41 provided on the usual starting handle 42, when the lever 35 is operated to lift the latch 24 and thus disengage it from the lever 22. The starting handle 42 is operatively connected by a toggle 43, reciprocating bar 44 and projection 45 to a starting lever 46 rotatably mounted on a vertical shaft 47, this starting lever carrying the usual stopping levers 48 and 49 which are pivoted thereon, the lever 48 being located in the path of a stopping pawl 50 which is pivoted at 51 on one of the cams 52 fixed on the main cam shaft so that it will engage and depress the upper stopping lever 48 as the main cam shaft completes its cycle of operation.

the stopping lever 48 acting on the stopping lever 49 to swing the lower end thereof rearwardly or toward the left in Figs. 1 and 2 and this portion of the lever 49 bearing against an arm 53 of a bell 5 crank lever 54 which is pivoted on the machine frame at 55, the bell crank lever having an arm 56 which is arranged to act on a collar 57 and to shift it in a direction to release or disengage the main driving clutch 58, this clutch driving the main cam shaft through a shaft 59 which carries the clutch and a pinion 60 on said shaft which cooperates with the gear 40 on the cam shaft 19, the stopping means just described being like that commonly used in machines of this 10 class and acting to stop the main cam shaft automatically upon completion of its cycle of operation. The starting lever 46 has a finger 61 thereon which is movable laterally above the stopping lever 48 and is engageable with the 15 stopping pawl 50 to disengage the latter from the stopping lever 48 when the starting lever 46 is rotated by movement of the starting handle 42 into starting position, as shown in Fig. 2, the dislodgment of the pawl 50 from the stopping lever 48 releasing the latter and the stopping lever 49 so that the clutch 58 may reengage and thus start the machine into operation. Since the lower portion of the lever 35 bears against the lug 41 on the starting handle and swings the latter into starting position when the lever 35 is actuated to lift or release the latch 24 from the lever 22, it will be understood that the machine will be automatically started by the lever 35 when operated to move the latch 24 into disconnected relation with the lever 22. As the cam shaft nears completion of its cycle of operation, the stopping pawl will act on the stopping levers 48 and 49 to actuate the bell crank 53 in a direction to release or disengage the clutch and thereby stop the operation of the machine, and since the lever 35 is returned to its initial position by the ejector lever 38 acting through the rod 34, movement of the starting lever 42 to its stopping position will not be interfered with by the lever 35.

Instead of automatically starting the machine into operation when the latch 24 is set in disengaged relation with the lever 22, means may be employed for actuating the latch 24 manually and independently of the starting means, so that the setting of the latch and the starting of the machine may be accomplished by two separate operations, such an arrangement having the advantage that it may be more readily applied to an outstanding machine. Such an arrangement is shown in Fig. 7 wherein a manually operative rod 62, provided with a handle 63 and guided by a bracket 64 located toward the front of the machine is operatively connected to the middle of the toggle 28 so that pushing of the rod 62 rearwardly will straighten the toggle and lift the latch 24, thereby disengaging it from the lever 22 as shown in Fig. 7 and pulling of the rod 62 forwardly will flex the toggle and thereby permit the latch 24 to descend and become engaged with the 50 stud 27 on the lever 22 when the latter moves into a position directly opposite to the lever 20 as shown in Figs. 4 and 5. Starting of the machine after the latch 24 has been set as desired may be accomplished by manipulation of the 55 starting handle of the machine.

A projection 65 may be fixed on the lever 20 to prevent overthrow of the toggle 28 when straightened or locked.

The operation of a machine embodying the 60 present invention as hereinbefore described is

as follows:—When the machine is to be operated in the conventional manner with keyboard composition of the matrix lines, the toggle 28 is flexed, either by permitting the lever 35 to stand in its normal retracted position after being brought to such position by the ejector lever 38 or by permitting the rod 62 to occupy its forward position, so that the latch 24 will engage the stud 27 on the lever 22 and the latter and the lever 20 will be connected by the latch so that they 10 will operate in unison. The first elevator receives the keyboard set matrix line by the usual means employed in machines of this class while the first elevator is supported in its normal line receiving position as shown in Fig. 1 or by the 15 full lines in Fig. 7, the rollers 21 and 23 of the levers 20 and 22 then bearing, under the weight of the elevator, on the section 15 of the cam 14, as shown in Fig. 4, and upon starting of the machine, which takes place in the usual manner, 20 the rollers 21 and 23 will be engaged by the low section 16 of the cam, thereby allowing the first elevator to descend to casting position, as shown by the dotted lines in Fig. 7, thereby presenting the matrix line in casting position in front of 25 the mold, and after a cast has been made from the line, the continued rotation of the cam will bring the raised section 17 thereof into engagement with the roller 23 on the lever 22, as shown in Fig. 5, and since this lever is connected to the 30 lever 20 by the latch 24 and the lever 20 is connected through the shaft 13 to the first elevator lever 11, the first elevator will be lifted to its upper or transfer level, as indicated by the dot and dash lines in Fig. 7, whereupon the matrices composing the line will be transferred to the usual second elevator 7 for transfer thereby to the usual distributing mechanism in the machine which returns the matrices to the channels in the magazine from which they were drawn, and the 40 continued rotation of the cam returns the section 15 of the cam to engaging position with the roller 23, thereby causing the first elevator to return to its normal line receiving level as shown in Fig. 1 and by the full lines in Fig. 7, the rotation of the cam shaft being stopped automatically by the stopping device, as hereinbefore described upon completion of its cycle of operation. In using the machine for casting from hand set lines, the first elevator head 8 is swung 45 forwardly, as for example indicated by the dotted lines in Fig. 7, while the first elevator is at its normal level or position and the line of matrices is inserted by hand or by the aid of a composing stick into the jaw portion 6 of the first elevator, 50 an example of a composing stick suitable for the purpose being disclosed in U. S. Letters Patent No. 1,740,435, granted December 17, 1929, and after insertion of the matrix line into the first elevator, the pivoted or hinged head thereof is 55 swung back to the position shown in Fig. 1 or into the full line position shown in Fig. 7. The latch 24 is then lifted by straightening of the toggle 28, either by pulling forward the upper end of the operating lever 35 in Fig. 1 or a pulling 60 forward of the rod 62 in Fig. 7, and the machine is started either automatically under the action of the lever 35 upon the starting handle 42 as described in connection with Figs. 1 to 3 inclusive or by manual manipulation of the starting handle 70 according to Fig. 7. The lifting of the latch 24 removes it from operative relation with the stud 27 on the lever 22, and the lever 20 will then become the controlling lever for the first elevator and the lever 22 will be in an idle or disconnected 75

relation therewith. Under these conditions, as the cam shaft rotates, the first elevator will be lowered from its normal position or level to its casting level as indicated by the dotted lines in Fig. 7 thereby presenting the matrix line in casting position in front of the mold, the roller 21 on the lever 20 riding from the cam section 15 to the lower cam section 16, and after the cast has been made, the continued rotation of the cam will 5 make, the continued rotation of the cam will 10 bring the section 18 thereof into engagement with the cam roller 21, and since the cam section 18 is of the same height or radius as the cam section 15 which positions the first elevator at its normal or line receiving level, the first elevator will be 15 returned from casting level directly to its normal or line receiving level as shown in Fig. 1 or by the full lines in Fig. 7. Although the roller 23 on the lever 22 will ride at this time on the high section 17 of the cam, the lever 22 is disconnected from 20 the lever 20 and from the first elevator so that the lever 22 will merely ride idly on its portion of the cam as shown in Figs. 1 and 7 and hence the first elevator will not be lifted to the upper transfer level but will remain at the normal line receiving level until the cam shaft completes its 25 cycle of operation and is stopped by its stopping means, at which time the cam section 15, of which the cam section 18 is a continuation, will be brought into engagement with the roller 21 on the lever 20. In the embodiment shown in Figs. 1 to 3 inclusive, the toggle 28 will be flexed automatically to permit the latch 24 to swing downwardly and reengage the stud 27, by the action of the ejector lever 38 on the rod 34 as the machine 30 nears completion of its cycle of operation, thus automatically resetting the machine for performance of its conventional cycle of operation of casting from keyboard set matrix lines and distributing the matrices therefrom, or the machine 35 may be reset for the performance of its conventional cycle by pulling forward the rod 62 and thereby flexing the toggle, according to Fig. 7. While the machine is at rest with its parts in normal position, it may be selectively set for the 40 performance of its conventional cycle or for casting from hand set lines by permitting the lever 35 to remain in its normal retracted position or pulling forward of this lever, or by setting the rod 62 in either its forward or its rear position according to whether the machine is to perform its 45 conventional cycle of operation casting from keyboard set lines or is to cast from hand set lines. The pivotal mounting of the first elevator head enables hand set lines to be inserted in the first 50 elevator conveniently and at a point nearest to the casting position and also enables removal of such lines after casting therefrom, at the earliest possible moment.

In each embodiment shown, the setting of the 55 latch determines which contour of the cam will control the movements of the first elevator during each operating cycle of the machine, the latch when in active position rendering effective the cam contour corresponding to the usual first 60 elevator cam contour which causes the first elevator to ascend to the usual transfer level before returning to its normal level and, when in inactive position, rendering effective the cam contour which causes the first elevator to return directly 65 to its normal level, without ascending to the higher transfer level. In the latter instance, therefore, the special matrices from the hand set odd line will not be conveyed to the distributor 70 and the capability of the machine for operation 75 in accordance with the usual or conventional cycle

will not be disturbed. Moreover, in each embodiment disclosed, the machine will be in condition, prior to each operating cycle thereof, for setting easily and quickly for selective use either for keyboard composing, casting and distributing in the usual or conventional manner or for casting only from hand set matrix lines, the invention enabling the casting unit of the machine to be readily rendered available for use alone or independently of the composing and distributing units 10 thereof.

We claim as our invention:—

1. In a typographical machine having a matrix line transporter, a plurality of controlling means for governing the movement of the transporter and operable to cause movement of said transporter successively from a normal line receiving position to casting and line removing positions and return thereof to said normal position to perform an operating cycle, or to cause movement of the transporter from said normal position to casting position and return thereof directly from casting position to said normal position to perform another operating cycle.

2. In a typographical machine having a matrix line transporter, actuating means therefor, and selective devices for governing the operation of said means on said transporter, said devices being operative to cause movement of said transporter successively from a normal line receiving position to casting and line removing positions and return thereof to said normal position to perform an operating cycle, or to modify the operation of the actuating means to cause said transporter to move from said normal position to casting position and to return directly therefrom to said normal position to perform a modified operating cycle.

3. In a typographical machine having a matrix line transporter, means embodying elements selectively operable at one setting to cause movement of the transporter from its normal position to convey a keyboard composed line received by it from its normal position to casting position and then to a position for removal and distribution of said line before returning to normal position to complete its cycle, or at another setting, to convey a hand composed line from said normal position to casting position and directly back to said normal position to complete its cycle and to permit removal of the hand composed line at said normal position.

4. In a typographical machine having a line transporting elevator, a cam having contours selectively operative respectively to cause descent of the elevator from its normal level to casting level and ascent from said casting level to line removing level above said normal level, and to cause descent of the elevator from its normal level to casting level and direct return therefrom to its normal level.

5. In a typographical machine having a line transporter, control means selectively operative to cause movement of the transporter from normal line receiving position successively to casting and line removing positions and return to normal position, or to cause movement of the transporter from normal position to casting position and direct return therefrom to normal position, driving mechanism for said means including a starting device therefor, and selecting means for said control means operative to actuate said starting device.

6. In a typographical machine having a line transporter control means therefor selectively

- operative to cause movement thereof from normal line receiving position successively to casting and line removing positions and return to normal position, or to cause return of the transporter directly from casting position to normal position, selecting means for said control means, and driving means for said control means including a starting device operative automatically by said selecting means when the latter is operated to set the control means for said direct return of the transporter from casting position to normal position.
7. In a typographical machine having a line transporting elevator, control means selectively operative to cause the conventional cycle of movements of the elevator from normal line receiving position successively to casting and line transfer positions and return from the latter position to normal position, or to cause return of the elevator directly from casting position to normal position, selecting means for said control means, and means for automatically setting said selecting means to cause the conventional cycle of movements of the elevator after said selecting means has been set to cause direct return of the elevator from casting position to normal position.
8. In a typographical machine having a line transporting elevator, a controlling cam therefor having different contours, controlling members cooperative respectively with said cam contours, selectively operative means for rendering said members operative to cause normal and modified cycles of movements of the elevator, driving means for said cam including a starting device operative automatically by the setting of said selectively operative means for the performance of the modified cycle of movements by the elevator, and means operative automatically upon completion of the modified cycle of movements of the elevator to set said selectively operative means for the performance of the normal cycle of movements by the elevator.
9. In a typographical machine having a line transporting elevator, controlling members one of which is connected to the elevator, means operative to selectively connect the other of said members to the elevator and to disconnect it therefrom, and a cam having contours cooperative with the respective members and shaped to respectively cause movement of the elevator from a normal intermediate position successively to a lower and then to an upper position and then return to said intermediate position, and to cause movement of the elevator from said normal intermediate position to said lower position and direct return from the latter position to said intermediate position.
10. In a typographical machine having a line transporting elevator, a pair of controlling levers one of which is connected to the elevator, means for connecting said levers for operation in unison and for disconnecting them to permit relatively independent operation thereof, and a cam having different contours with which said controlling levers cooperate respectively.
11. In a typographical machine having a line transporting elevator, a duplex controlling cam therefor having contours certain sections of which are similar and other sections of which differ, a pair of controlling members cooperative respectively with said cam contours, and means for selectively rendering one or the other of said members operative with respect to the elevator to control its movements.
12. In a typographical machine having a line transporting elevator, a pair of controlling levers, means for connecting one of said levers to the elevator, a latch for selectively connecting and disconnecting said levers for conjoint or relatively independent operation, and a cam having different contours with which said levers cooperate respectively.
13. In a typographical machine having a line transporting elevator, a pair of controlling levers one of which is connected to the elevator, a latch carried by one of the levers and engageable and disengageable with respect to the other lever to render them operative in unison or independently, means including a toggle connected to said latch for selectively setting it in engaged or disengaged position, and a controlling cam having different contours with which said levers cooperate respectively.
14. In a typographical machine having a line transporting elevator, a pair of controlling levers one of which is connected to the elevator, means for selectively connecting and disconnecting said levers for conjoint or relatively independent operation, a controlling cam having different contours, the lever connected to the elevator cooperating with one of the cam contours under the weight of the elevator, and means acting on the other lever to maintain it in cooperation with the other cam contour when said levers are disconnected.
15. In a line casting machine having a line transporter and means normally operative automatically to cause the transporter to move from one to another of several operating positions, means selectively operative automatically to cause the transporter to move from one to the other of certain only of said operating positions.
16. In a line casting machine having a line transporter normally movable from a starting position through a plurality of operating positions to a final stopping position during one complete cycle of operation of the machine, and common means operative automatically to prevent movement of the transporter through all of the operating positions and terminate its movement at the final stopping position.
17. In a typographical machine having a matrix line transporter, controlling means having selective connections therefrom to the transporter and normally operative to impart a given set of movements to the transporter during one cycle of operation of the machine, and operative upon adjustment of said selective connections to impart a different set of movements to the transporter during another operating cycle of the machine.
18. In a typographical machine, the combination of a line transporting elevator having a line receiving head thereon movable into a position to receive hand-composed matrix lines and into position to present such lines in casting position, means including a cam for controlling the movements of said elevator, a starting device for starting the operation of said cam, and a starting handle cooperative with said starting device and extending into proximity to the line receiving head of the elevator.
19. In a typographical machine, the combination of a line transporting elevator having a matrix line receiving head movable thereon into position to receive hand-composed lines, controlling means for the elevator for causing it to con-

vey lines to casting position, a starting device for starting the operation of said elevator controlling means, and a starting handle extending from said starting device into proximity to the movable head of the elevator.

5 20. In or for a typographical machine having a movable transporter to carry a matrix line to and from position before a slug casting mold,

transmission mechanism comprising means for imparting different cycles of movement to said transporter, and selective control means associated with said transmission mechanism for causing it to impart to said transporter one or another cycle of movement.
